[57] CLAIM

The ornamental design for an display case, as shown and described.

DESCRIPTION

FIG. 1 is a front elevational view of an display case showing our new design;

FIG. 2 is a top plan view thereof;

FIG. 3 is a right side elevational view thereof, the left side being a mirror image thereof;

FIG. 4 is a bottom plan view thereof;

FIG. 5 is a rear elevational view; and,

FIG. 6 is a perspective view thereof.

The use of full and partial circles as shown in FIGS. 1, 3 & 6 represent spheres within the borders shown. The spheres are continuous throughout the entire bordered area.

FIG. 1

FIG. 2

FIG. 3

FIG. 4

FIG. 5

FIG. 6
